AUTOMATIC SWITCH

Original Filed March 14, 1923

UNITED STATES PATENT OFFICE

JOHN ERICKSON, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE

AUTOMATIC SWITCH

Application filed March 14, 1923, Serial No. 694,994. Renewed June 27, 1930.

The present invention relates in general to automatic switches, although certain details are not confined specifically thereto; and has for its object the provision of certain mechanical improvements tending to make such switches more easily adjustable, together with the addition of other desirable features which tend to make such switches more rugged and durable.

- 10 The invention is illustrated in the accompanying drawings, in which Fig. 1 is a side view of a switch of the same general type as that described in the U. S. Patent #1,107,153, granted August 11, 1914 to Clement, being, 15 however, of the particular type shown and described in Automatic Telephone Practice, third edition, by Harry E. Hershey. Figure 2 is a front view of the switch shown in Fig. 1. In order to avoid complicating the drawing unnecessarily, the bank contact assembly and the driving magnet interrupter contacts have been omitted in Fig. 2. Figure 3 is an end view of the driving magnet and associated parts.
- 20 Referring now particularly to Fig. 1, the bank of contacts shown therein is indicated generally by the reference numeral 2. This bank of contacts is adapted to be wiped over by the double ended wiper 4 and is so arranged with respect to the wiper that as one arm of the latter passes off the last bank contact in rotating, the other wiper arm comes into engagement with the first contact. In this specific switch, instead of providing a common plate in the bank for each wiper with which one of the arms of that wiper is in constant engagement, a brush extends to and makes continuous contact with each of the wipers. The terminal of the brush that makes contact with the wiper 4 is the terminal 11.
- 25 The wiper 4, being a test wiper, has its two contact tips flattened out so as to be able to come into engagement with a second contact before it is out of engagement with the one from which it is passing. The remaining wipers 5-7, inclusive, Fig. 2, however, being line wipers, have their tips so shaped that only one contact at a time is engaged by one of these wipers. The ratchet wheel 13 and
- the wipers 4-7, inclusive, Fig. 2, are rigidly secured to the common spindle 9 which is rotatably mounted in frame 8.
- 30 The ratchet wheel 13 and likewise the aforesaid wipers are driven by the driving magnet 10. When the said magnet is energized, it attracts the armature 19, the top end of which is forced to the right against the tension of the spring 21. The pawl 17, carried by the armature 19, is caused to engage another tooth in the ratchet wheel 13 by the pawl spring 18. When the said magnet 10 deenergizes, the spring 21 draws the armature 19 and likewise the pawl 17 to their former position, at which time the armature 19 is resting against the eccentrically adjustable back stop 31, as can be seen most clearly in Fig. 2. The pawl 17, in returning to its normal position, advances the wipers 4-7, inclusive, into engagement with the next set of contacts. This operation may be repeated as often as desired.
- 35 It was pointed out above that the eccentrically pivoted back stop 31 limits the backward stroke of the armature 19. The forward stroke of the armature 19, it may be stated, is limited by the soft iron pole piece 29, Figs. 2 and 3, which is screwed into a threaded hole in the armature 19 and which is retained in its set position by the stiff spring washer 30.
- 40 Referring to the construction of the bank 2, it is seen that the said bank is assembled entirely on the bank frame 3 which is cut from a single piece of heavy sheet metal and is attached to the switch mechanism by the screws 5' and 6'. The set screw 7' is provided for the purpose of enabling the switch wipers to be accurately centered on the bank contacts by adjusting the bank frame 3 so that it is closer to or farther from the switch frame 8. The longitudinal adjustment between the frames 3 and 8 is made possible owing to the fact that the hole in the set screw 7' through which the screw 6' passes is purposely made very much larger than the screw 6', and owing also to the fact that the screw 5' passes through a slot in the frame 8, which slot can be seen in Fig. 2.
- 45 One of the features of the invention relates to the improved pawl 17 together with

100

its bearing and the way in which it is operated upon by the pawl spring 18. As can be readily seen by inspecting Figs. 1 and 2, the pawl 17 is cut from a piece of heavy sheet metal and is bent in the shape of an inverted 5 **U** and retains this shape along its length almost to the tip, thereby giving it the necessary stiffness and strength.

Referring to the pawl spring 18, one end 10 of this spring passes through a hole in the end of the armature 19, while the other end passes through a hole (not shown) in the pawl 17. This spring, it will be noted, while pulling the pawl 17 in such a direction as to cause it to lie snugly against the ratchet wheel 13, also pulls the pawl 17 back snugly against the armature 19 so that in case the bearing has a small amount of play, the pawl 17 is 15 not hammered back and forth as the armature 19 vibrates, as would be the case if the spring 18 were so positioned as to merely pull the pawl 17 upward instead of upward and backward as it does.

The armature 19 is provided with a bushing 32 (Fig. 2), which gives extra bearing 25 surface for the hollow bearing pin 15 which passes through the pawl 17 and the aforesaid bushing 32, and which is spread at the ends to hold it in place.

30 In order that the tension on the armature spring 21 be readily adjustable, the adjusting member 22 is slidably mounted on the switch frame 8 by the machine bolt 23, which passes through the slot 24, and the pivot pin 25. This pivot pin 25, therefore, serves the 35 double purpose of pivoting the armature 19 and furnishing a back stop for the adjusting member 22, which would otherwise be rotated around the machine screw 23 by the spring 21.

40 In order that the further utility of the sliding adjusting member 22 be appreciated, it may be pointed out that the switches are mounted side by side and close together in 45 the position of Fig. 2. When the switch is mounted in this position, the tension of the spring 22 is adjusted by first loosening the bolt 23 with a small flat wrench and then sliding the member 22 either back or forward as the case may be, after which the screw 23 is 50 tightened to hold the member 22 in its set position.

The adjusting member 22 has the still further function of holding the pivot pin 25 in 55 position, keeping the same from sliding longitudinally and also preventing the pin 25 from rotating. These results are accomplished by providing the pin 25 with a notch into which the member 22 fits snugly, as can 60 be seen in the drawing. This pin is notched on one side only and is not provided with a groove extending all the way around the pin for the reason that it is desired that the pin 65 always remain in one position so that in case it is not mechanically perfect or is slightly

bent, the adjustment of the armature is retained, which would not be the case if the pin were permitted to rotate.

It is well understood that the pin 25 could be secured so that it would not move longitudinally or rotate by any one of a number of means, such as flattening the ends. If the pin were secured in this way, however, it could not be readily removed in order to permit the removal of the armature 19 or the magnet 10, which may become desirable in case either is found to be defective or unsatisfactory. It will be seen, however, that the arrangement shown in the drawing is such that the pin 25 may be easily removed by merely raising the adjusting member 22 out of engagement therewith and drawing the pin 25 out from either side.

The bearing surface of the armature 19 is increased by the bushings 27 and 28, as can 85 best be seen in Fig. 3. This broader bearing surface gives the switch a longer life by distributing the wear over a greater area.

Another feature of improvement contained 90 in the present switch structure is the extension of the spring mounting bracket 26 so that the bracket forms an auxiliary support for the pivot 25, as can be seen best in Fig. 2. This has the effect of stiffening the pivot 25 and also of preventing the switch frame in 95 which the armature 19 is mounted from springing slightly when the magnet 10 energizes.

What is claimed is:

1. In an automatic switch, the combination, with a ratchet wheel and an armature, of a pawl operated by the armature for driving the ratchet, said pawl constructed of sheet metal folded to give a **U** shaped cross section, two ears at one end of said pawl disposed on opposite sides of said armature, a pivot passing through said ears and the armature, and a spring having one end attached to the end of the armature at a point beyond the pivot and the other end attached to the pawl at a point between the pivot and the driving end of the pawl, the parts being so arranged that the spring holds the driving end of the pawl against the ratchet wheel and at the same time pulls the pawl against the pivot substantially in line with the direction in which driving force is applied to the ratchet, thereby preventing play in the pivot during operation.

2. A spring adjusting device for switches mounted close together, comprising a bracket adjustably attached to the frame of a switch between such switch and the one next to it, an arm on said bracket to which the motor magnet spring is attached, and a second arm for said bracket extending out between the switches where it can be easily reached when it is desired to adjust the bracket to regulate the spring tension.

3. The combination, with a switch magnet armature, of a pivot rod for said armature notched at one end, and an armature spring adjusting bracket attached to the switch frame, said bracket having an arm lying in the notch in said rod, whereby the rod holds the bracket in position and the arm prevents the rod from turning and from moving endwise.
- 10 4. The combination, with a switch magnet armature, of a pivot rod for said armature notched at one end, and an armature spring adjusting bracket attached to the switch frame at a single point, said bracket having an arm lying in the notch in said rod, whereby the rod prevents the bracket from turning about its supporting means and the arm retains said rod in position.
- 15 5: In combination, a switch frame comprising a vertical member, a horizontal member extending at right angles to said vertical member, and two other horizontal members parallel to said first horizontal member, a magnet core secured at one end to said first horizontal member and having the other end disposed between said other horizontal members, a pivot rod extending through the said other horizontal members, an armature for said magnet core pivoted on said rod at two points inside said other horizontal members, contact springs operated by said armature, and a spring mounting bracket having one end secured to said first horizontal member and having the other end bearing against said pivot rod between the points at which the armature is pivoted, said bracket serving to brace the frame and stiffen the pivot rod.
- 20 6. The combination, with a switch driving magnet secured to the switch frame and an armature pivoted on a rod extending through extensions of said frame, of a spring mounting bracket acting as a brace for the frame and said extension when the magnet is energized and acting also as a support for said rod between said extensions.
- 25 7. In an automatic switch, the combination, with a ratchet wheel and an armature, of a pawl operated by the armature for driving the ratchet, a pivot rod for rotatably mounting said pawl on said armature, and a spring having one end attached to the end of the armature at a point beyond the pivot and the other end attached to the pawl at a point between the pivot and the driving end of the pawl, the parts being so arranged that the spring holds the driving end of the pawl against the ratchet wheel continually and at the same time pulls the pawl against the pivot substantially in line with the direction in which driving force is applied to the ratchet, thereby preventing play in the pivot during operation.
- 30 8. The combination, with a switch magnet armature, of a pivot rod for said armature notched near one end, and an armature spring adjusting bracket slidably mounted on the switch frame and secured at a single point, said bracket having an arm lying in the notch in said rod, whereby the rod prevents the bracket from turning about said point and the arm prevents the rod from rotating and from moving endwise.
- 35 9. A switch for use in automatic telephone systems having rotatable wipers in which the pawl for operating the ratchet wheel is constructed from a single piece of sheet metal bent in the shape of a U with one edge of the base of the U suitably shaped to engage with the teeth of the ratchet wheel.
- 40 10. In an automatic switch for telephone systems, a set of bank contacts, a set of wipers having access to said contacts, a motor magnet having an armature adapted to operate a pawl and ratchet wheel to rotate said wipers over said bank contacts, said pawl comprising a single U-shaped sheet of metal having extensions of the two legs pivoted to the end of said armature and one edge of the base of the U flattened out to engage with the teeth of said ratchet wheel.
- 45 In witness whereof I hereunto subscribe my name this 10th day of March, A. D. 1923.
